(57) **CLAIM**

The ornamental design for a tire, as shown and described.

DESCRIPTION

FIG. 1 is a side perspective view of a tire showing our new design, it being understood that the tread pattern is repeated throughout the circumference of the tire, the opposite side being the same as that shown;

FIG. 2 is a front elevational view of the tire with section lines related to FIG. 5;

FIG. 3 is a side elevational view of the left side of the tire;

FIG. 4 is a side elevational view of the right side of the tire;

FIG. 5 is an enlarged fragmentary view taken along line 5-5 of FIG. 2;

FIG. 6 is a first transversal section view of the tire taken along line 6-6 of FIG. 8;

FIG. 7 is a second transversal section view of the tire taken along line 7-7 of FIG. 8; and,

FIG. 8 is an enlarged fragmentary view of FIG. 2 with section lines related to FIG. 6 and FIG. 7.

In the drawings, the broken lines depict environmental subject matter that form no part of the claimed design.
